UNITED STATES PATENT OFFICE.

ARTHUR BESSEY SMITH, OF EVANSTON, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,368,850.

Specification of Letters Patent. Patented Feb. 15, 1921.

Application filed June 18, 1917. Serial No. 174,444.

To all whom it may concern:

Be it known that I, ARTHUR BESSEY SMITH, a citizen of the United States of America, and a resident of Evanston, county 5 of Cook, and State of Illinois, have invented certain new and useful Improvements in Automatic Telephone Systems, of which the following is a specification.

My invention relates in general to automatic telephone systems, but more particularly to methods of automatic calling between widely separated automatic exchanges interconnected by toll or long distance lines. In this respect the present invention may be 15 considered as an improvement on the invention disclosed in my prior application Serial No. 96,493.

By the present invention automatic switches at a distant exchange may be controlled by impulses of alternating current, transmitted over a toll line by means of an operator's calling device, and translated into the usual two wire interruptions by a repeater located at the distant end of the toll line. There is no current flow on the toll line during conversation to maintain the connection, but instead the repeater is provided with a locking relay which holds the line circuit for the automatic switches closed, 25 except for the momentary operating interruptions. Release is accomplished by transmitting alternating current of different frequency over the toll line, the repeater at the distant end being provided with two tuned relay bridges, one of which is responsive to operating current and the other being responsive to releasing current to unlock the relay before mentioned to release the automatic switches. Since the alternating currents employed for operating and releasing purposes are transmitted over the talking circuit, it is possible to use my invention in connection with phantom toll circuits, or in connection with toll lines or phantom lines 35 upon which simplex telegraph circuits are superimposed, thereby greatly increasing the efficiency of a toll line system.

The particular means employed in carrying out my invention will be described, and 40 a detailed explanation of the working thereof will be given hereinafter, reference being had to the accompanying drawings, in which Figures 1 and 2, when taken in order with

the lines at the ends thereof in alignment, represent diagrammatically a complete circuit connection between a calling substation A and a called substation A' in a system embodying the principles of my invention. The connection has been established through the medium of the cord circuit O, the toll line comprising conductors 50 and 51, the repeater E (Fig. 2), and the connector F.

Referring now to Fig. 1 of the drawings, the substation A may be of any suitable or approved type, and as shown herein consists 55 of the usual common battery arrangement in which the transmitter and receiver are connected in series. The line conductors 12 and 13 extend to the exchange where they have allotted to them the usual line and cut-off relays 2 and 3, the answering jack J, and the line lamp L.

The cord circuit O may also be of any suitable type. As shown herein it comprises essentially a bridge battery supply relay 5 which in conjunction with the sleeve relay 7 controls the supervisory lamp L'; and the ringing up locking relay 6 which in conjunction with the sleeve relay 8 controls the supervisory lamp L''. Key K is a ringing 75 key, key K' is the usual listening key, while the key K'' is a combined ringing and calling device key. The reference character CD indicates a calling device which may be of the general type of calling device disclosed 80 in the British patent to Dicker No. 29,654 of 1910. The impulse springs of the calling device, however, are so designed that when the calling device is operated they will produce momentary closures of the circuit in which 85 it is included instead of the usual momentary interruptions.

The toll line 50—51 may be provided at the exchange in which the line of substation A terminates with the regular multiple jacks, 90 one of which is shown at J'. Associated with the jack J' is shown a drop 20, a visual busy signal 21, and a group of three relays, of which the relay 24 is the usual cut-off relay, while relays 22 and 23 are special 100 relays which at the proper time transmit alternating current over the toll line for releasing purposes. The relay 23 also has the function of disconnecting the repeater E'.

At the distant exchange the toll line 50—51 105 is provided with the multiple jack J' and

the associated drop 52 and visual busy signal 53. The relays 54, 55 and 56 correspond to the relays 22, 23 and 24, respectively, which are associated with the jack J' , and need not 5 be again described.

The repeater E , as before mentioned, is capable of transforming alternating current impulses which are received over the toll line into the ordinary circuit interruptions 10 which are commonly used for controlling two wire automatic switches; it comprises a pair of condensers 90 and 91 in the talking circuit, a pair of tuned alternating current relay bridges, and a plurality of relays comprising relays 67 to 72, inclusive. The functions of these relays will be explained in the description of the operation during the establishment of a connection. One of the 15 alternating current bridges, comprising the alternating current relay 62, condenser 64, and impedance coil 66, is tuned to the frequency of the generator Gen' at the first exchange and is used for controlling the operation of the automatic switches. The 20 other bridge, comprising the alternating current relay 61, the condenser 63, and the impedance coil 65, is tuned to the frequency of the generator Gen^2 , and has the function of controlling the release. The alternating 25 current relays 61 and 62 are of special design and respond to alternating current in the same way as the ordinary relay does to direct current. For example, the relay 62 attracts its armature once for each impulse 30 of alternating current, but does not respond to each separate alternation which goes to make up a single current impulse. In regard to the current frequencies employed, I do not wish to limit myself to any particular values. It has been found in practice, 35 however, that an operating current of 100 cycles per second will give good results. The release current which is produced by the generator Gen^2 may have a frequency of 50 40 cycles per second. These frequencies are high enough so that no interference will occur, due to the ordinary ringing currents which are preferably of a frequency of approximately 20 cycles per second. The apparatus 45 at both ends of the toll line 50-51, although not shown in exactly the same position in the drawing, is nevertheless in duplicate. Thus the repeater E' in Fig. 1, is similar to repeater E in Fig. 2. The generator Gen^3 in Fig. 2 corresponds to generator Gen^2 in Fig. 1; and it is to be understood that the operator at whose position the jack J^2 is located may be provided with a cord circuit similar to the cord circuit O 50 and having associated with it a generator of the same frequency as the generator Gen' .

Directly connected with repeater E is shown a connector F which may be of the general type of connector switch disclosed 60 in U. S. Letters Patent No. 815,176 granted

March 13, 1906, to Keith, Erickson, and Erickson; the circuits being modified, however, in accordance with the two wire system of control. A connector switch of the foregoing type may be given access to a plurality of subscribers' lines and is operable in response to the digits of a called number to establish connection with any one of the lines to which it has access. It will be understood, of course, that a selector switch of any suitable construction may be inserted between the repeater E and the connector F in the usual manner in order to increase the capacity of the system. One of the lines to which the connector F has access is the line 70 which is shown in the drawing as extending to the substation A' . The mechanism indicated by the reference character C is an individual line switch associated with the line of substation A' and is provided for the purpose of extending connection to an idle selector switch when the said line is calling. An individual line switch similar to the one herein shown is disclosed in the patent to Newforth No. 1,078,690 granted November 18, 1913. 75

Superimposed on the toll line 50-51, I have shown a simplex circuit including the two sides of the toll line in parallel, and the conductors 200 and 201 at opposite ends 80 thereof. These conductors 200 and 201 each terminate in a well known type of quadruplex telegraph apparatus shown herein diagrammatically and indicated by the reference characters $QUAD'$ and $QUAD^2$. This 85 equipment may be used for straight telegraph circuits; or, in case the toll line 50-51 is a phantom circuit instead of a physical circuit, the polar and neutral sides of the "quad" may be used as the switch control 90 circuits for the two physical lines, respectively, upon which the phantom is superimposed. An arrangement of this character is shown in my prior application Serial No. 86596. 95

While I have shown throughout the drawings a plurality of batteries, it is to be understood that there is preferably but one battery for each exchange, each having its positive pole grounded. In order not to encumber the drawings, separate reference characters have not been applied to the individual batteries shown, and to avoid misunderstanding, it will be stated that where in the following description, a circuit is 100 traced "to battery" it extends to the live or ungrounded pole of one of the exchange batteries. The ringing equipment IR and the busy signaling machine Q , which are shown associated with the connector F , are 105 of the well known type and need no detailed description. 110

The operation of the system can best be understood by describing the process of establishing a connection and a description of 115

this operation will now be given. For this purpose, it will be assumed that the subscriber at substation A desires to obtain a connection with the subscriber at substation A', this being the complete circuit connection shown in the drawing and previously referred to. Upon the removal of the receiver at substation A, a circuit is completed for the line relay 2 thereby causing the illumination of the line lamp L. In this manner the attention of the operator is attracted and she will respond by inserting the answering end of the cord circuit O in the answering jack J. A circuit is therefore completed including the sleeve relay 7 and the cut-off relay 3, whereby the line relay 2 is disconnected and the lamp L is extinguished. In addition, the battery supply relay 5 in the cord circuit is energized over the calling subscriber's loop and prevents the illumination of the supervisory lamp L'. The operator will now throw her listening key K' in order to obtain from the calling subscriber the usual information concerning the name and number of the party wanted, etc. Although the operations described in the foregoing are purely manual in their character, it will be understood that the exchange may contain also automatic lines which may have access to the toll operator through the medium of any well known type of automatic switching mechanism.

Since it has been assumed that the desired party is the subscriber at substation A' in the distant exchange, the operator will now insert the calling plug of the cord circuit O in the jack J', the idle or busy condition of the toll line being first determined by testing with the tip of the plug in the usual manner. When the plug is inserted in the jack the following circuit is established: ground at G', winding of sleeve relay 8, sleeve of plug, sleeve of jack J', winding of relay 22, and the winding of relay 23 to battery. Relays 8, 22, and 23 are energized over the above circuit, the former relay opening the test circuit extending to the operator's head set and preparing a locking circuit for relay 6. The energization of relay 22 has no immediate effect. Relay 23, however, disconnects the conductors 27 and 28 which extend to the repeater E' from the line conductors 25 and 26, respectively; and also closes parallel energizing circuits for the cut-off relay 24 and the visual busy signal 21. The cut-off relay, upon energizing, disconnects the drop 20. The visual busy signal 21 is one of a plurality of such signals located at different operators' positions which are all operated in multiple.

The operator will now throw her calling device key K', thereby bridging the calling device CD and the generator Gen' in series across the tip and ring strands at the calling end of the cord circuit. The calling device

is now operated in accordance with the first digit of the desired number, resulting in the closure of the bridge a plurality of times at the impulse springs of the calling device. At each closure of the bridge an impulse of alternating current from generator Gen' is transmitted over the toll line through the repeating coils R and R' to the distant exchange, causing the operation of the alternating current relay 62. It is noted that relay 62 is connected in bridge of the heavy talking conductors 59 and 60 which in turn are connected by way of normally closed contacts of relay 55 with the heavy talking conductors 57 and 58, respectively, and the operation of this relay therefore will be sufficiently obvious. The alternating current relay 61 does not respond at this time because the bridge in which it is included is not tuned to the frequency of the generator Gen'. Neither does the drop 52 respond, for it is adjusted either by means of a heavy armature or by tuning its circuit so that it will be actuated only by low frequency currents. It should be mentioned also that the condensers 96 and 91 are of very low capacity in order to prevent leakage of an appreciable amount of current through the line relay 100 of the connector F.

From the foregoing it will be clear that at each closure at the bridge by the calling device CD, an impulse of high frequency alternating current is transmitted over the toll line to the distant exchange to operate the alternating current relay 62. When the relay 62 energizes in response to the first current impulse, a circuit is completed for the relay 69 as follows: ground at G', armature 76 and its working contact, contact 83, spring 82, and the winding of relay 69 to battery. A branch of this circuit extends through the relay 68 to battery. Upon energizing, relay 69 completes a locking circuit for itself as follows: ground at G', spring 93, contact 92, working contact of armature 81, armature 81, spring 82, and the winding of the said relay 69 to battery. A continuation of the above circuit may be traced through the cut-off relay 56 as follows: armature 81, upper winding of the electropolarized relay 71, armature 77 and its resting contact, and the winding of the cut-off relay 56 to battery. Upon energizing, relay 56 disconnects the drop 52. A branch of the energizing circuit of relay 56 extends through the visual busy signal 53 and its multiples to battery, thereby making the toll line terminating in jack J' busy to the operators at the second exchange. The upper winding of relay 71 is a polarizing winding only, and does not have a sufficient number of turns to enable the relay to energize. When the relay 68 was energized in multiple with relay 69, it established a locking circuit for itself over the following path: 125 130

ground at G^7 , armature 86 and its resting contact, armature 80 and its working contact, and the winding of the said relay 68 to battery. A further result of the energization of relay 69 is the closure of the circuit for the line relay 100 of the connector F as follows: ground at G^8 , lower winding of line relay 100, contact springs controlled by the lower armature of relay 106, conductor 74, working contact of armature 84 of relay 69 and the said armature, armature 85 and its resting contact, the lower winding of relay 71, conductor 73, contact springs controlled by the upper armature of relay 106, 10 and the upper winding of the line relay 100 to battery. Upon the closure of the above circuit, relay 71 is not energized owing to the fact that its two windings are connected in opposition. The line relay 100, however, 15 attracts its armature and closes the usual energizing circuit for the slow acting release relay 101. Upon energizing, relay 101 prepares circuits for the vertical and rotary magnets 107 and 108.

20 The foregoing operations have all occurred in response to the energization of the alternating current relay 62 by the first current impulse received over the toll line. When the current ceases to flow, the relay 62 de- 25 energizes and closes a circuit for relay 70 as follows: ground at G^8 , armature 76 and its resting contact, working contact of armature 79 and the said armature, and the winding of relay 70 to battery. Upon energizing, 30 relay 70 opens the locking circuit of relay 68 at armature 86 and at the same time closes an energizing circuit for the slow acting relay 72. This latter relay upon energizing, 35 short-circuits the lower winding of the relay 40 71. Upon the opening of its locking circuit, relay 68 de-energizes and opens the circuit of relay 70, which relay also accordingly de-energizes. Inasmuch as armature 85 of relay 70 is included in the circuit of the line relay 100 45 of the connector F, the momentary energization of the relay 70 which has just been described causes an interruption of the circuit of the line relay. When the relay 62 is energized in response to the next alternating current impulse, and subsequently de- 50 energizes at the end of the impulse, relays 68 and 70 operate as before to produce another interruption of the circuit of the line relay 100. These operations occur quite rapidly and since the slow acting relay 72 receives an impulse at each energization of relay 70, it maintains its armature attracted 55 continuously during a series of impulses to maintain a circuit around the lower winding 60 of relay 71.

As explained, each energization of relay 70 produces an interruption of the circuit of the line relay 100 of the connector F. In response to these interruptions of its circuit, 65 the line relay 100 is de-energized a number of times, and at each de-energization, transmits an impulse from ground G^8 through the slow acting relay 102 and the vertical magnet 108 to battery, side switch wiper 112 being in its first position. In response to 70 these impulses, the vertical magnet is operated to raise the switch shaft step by step until the wipers 140, 141, and 142 arrive at the horizontal level of bank contacts in which is located the terminal of the line 75 of substation A'. The relay 102 is energized in series with the vertical magnet and being slow acting, retains its armature during the series of impulses to close a circuit for the private magnet 110. At the end of the 80 series of impulses, relay 102 and the private magnet 110 de-energize, the latter advancing the side switch wipers 112 and 113 to second position in the well known manner.

The operator will now manipulate her 85 calling device CD in accordance with the second and in this case the final digit of the called number, thereby transmitting a second series of alternating current impulses over the toll line and causing a second series of energizations of the alternating current relay 62. Relays 68 and 70 respond as before, the latter relay producing a second series of interruptions in the circuit of the line relay 100 of the connector F. The line 90 relay 100 is accordingly again de-energized a number of times and now, side switch wiper 112 being in its second position, transmits at each de-energization an impulse from ground G^8 through the relay 102 and 95 the rotary magnet 107 to battery. In response to these impulses, the rotary magnet is operated to rotate the switch shaft step by step until the wipers 140, 141, and 142 arrive at the particular set of contacts in 100 which the line of substation A' terminates. The slow acting relay 102 and the private magnet 110 are energized as before and at the end of the final series of impulses, assuming that the called line is idle, the private magnet advances the side switch wipers to third position. By the advance of the side switch wiper 113 to third position, a circuit is completed for the cut-off winding of the line switch C as follows: ground at 110 G^9 , side switch wiper 113 in third position, private wiper 141, bank contact 144, and the cut-off winding 145 to battery. By the operation of the cut-off armature 146 the line of substation A' is cleared of its normal battery and ground connections in the line switch C. As a further result of the 115 advance of the side switch wipers to third position, a circuit is completed in an obvious manner for the line switching relay 105, 120 which relay is accordingly energized to complete a signaling circuit as follows: ground at G^{10} , the ringing current generator, contact of interrupter IR, conductor 147, 125 resting contact of armature 148 and the said 130

armature, lower armature of relay 105 and its working contact, line wiper 142 and the bank contact engaged thereby, to and through substation A', returning over the 5 upper line conductor to the bank contact engaged by the line wiper 140, working contact of the upper armature of relay 105 and the said armature, armature 149 and its resting contact, and the lower winding of relay 104 to battery. By the operation of the 10 ringing interrupter IR, a small booster battery is substituted at intervals for the ringing current generator thereby producing an intermittent operation of the ringer at substation A'. The relay 104 is adjusted so that it will not energize when the receiver at substation A' is on the hook.

The operator at the originating exchange, having finished dialing the wanted number, 20 will now restore her calling device key K² to normal position, whereby the calling device CD is made available for use in establishing other connections.

When the called subscriber removes his 25 receiver in response to the ringing of his bell, the relay 104 at the connector F is energized and completes a locking circuit for itself as follows: ground at G¹, off-normal springs 151 (closed at the first upward 30 movement of the shaft), working contact of armature 152 and the said armature, and the upper winding of relay 104 to battery. As a further result of the energization of relay 104, the lower winding of this relay and 35 the lead to the ringing equipment are disconnected and the called end of the talking circuit is finally completed. Current for the transmitter at substation A' is supplied through the windings of the answering 40 bridge relay 106 in the usual manner, and the relay 106 is therefore energized to reverse the conductors 73 and 74 as regards their connections to the windings of the line relay 100. The direction of current flow 45 in the lower winding of relay 71 is therefore reversed, and since its two windings now assist each other, the relay 71 is energized. By the operation of relay 71, the low capacity condensers 90 and 91 are short-circuited at the armatures 87 and 88 respectively. The complete talking circuit has 50 now been established and conversation may proceed as desired, the voice currents following the path shown in the heavy lines.

55 When the subscribers are through talking, they will both replace their receivers. By the replacing of the receiver at substation A, the relay 5 in the cord circuit O is de-energized to give the operator a disconnect signal by the illumination of the supervisory lamp L'. The disconnection, including the release of the automatic switches at the distant exchange, is accomplished by taking down the cord circuit O. When the calling 60 plug is removed from the jack J', the ener-

gizing circuit of the relays 22 and 23 is broken. Since relay 23 is slow acting it will retain its armatures in operated position for an instant after the relay 22 has de-energized, thereby bridging the generator Gen² momentarily across the conductors 25 and 26 of the toll line. It follows that an impulse of alternating current will be transmitted by way of the repeating coil R, the toll line conductors 50 and 51, and the repeating coil R' to the distant exchange, where it serves to operate the alternating current relay 61 connected in bridge of conductors 59 and 60. The alternating current relay 62 does not respond at this time. Upon energizing, relay 61 closes an energizing circuit for relay 67. Relay 67, upon energizing, breaks the locking circuit of relay 69 and the circuit which includes the upper winding of relay 71 and the cut-off relay 56, and at the same time 85 closes at its armature 78 a circuit for the cut-off relay 56 which is independent of the relay 69. Thus the cut-off relay 56 is maintained energized to obviate any danger of the drop 52 being actuated by the comparatively low frequency releasing current. When its locking circuit is opened, relay 69 de-energizes and at its armature 84 opens the circuit of the line relay 100 of the connector F. The de-energization of relay 100 is followed by the de-energization of the release relay 101, whereupon a circuit for the release magnet 109 is closed in the usual manner. By the energization of the release magnet, the connector F is restored to normal, the 100 circuit of the release magnet 109 being broken by the shaft when it reaches its lowest position. It will be seen then, that upon the withdrawal of the calling plug of the cord circuit from the jack, an impulse of 105 alternating current of a lower frequency than the current used for operating purposes is transmitted over the toll line to energize a relay in a tuned bridge at the opposite end thereof, to bring about the release of the 110 automatic switches involved in the connection. It has been assumed in the foregoing explanation, that the line of substation A' was idle when called. If this line had been busy, the test relay 103 would have energized 115 in series with the private magnet 110 at the end of the final series of impulses, in order to prevent the completion of the connection to the called line and to transmit a busy signal from the busy signaling machine Q to the 120 calling subscriber. The low capacity condensers 90 and 91, which are shunted around the normally open contacts in the talking circuit controlled by the relay 71, enable the calling subscriber (and the operator if she 125 has her listening key thrown) to hear the busy signal, and are provided for this purpose.

In regard to the simplex circuit superimposed on the toll line, and the quadruplex 130

- apparatus at each end thereof, the use of equipment of this character for telegraph circuits is well known and will need no detailed explanation. In the case of a phantom circuit, this quadruplex equipment may be used for automatic switch control circuits associated with the two side lines, in the manner disclosed in my prior application Serial No. 86596, previously referred to; 5 while connections over the phantom circuit are established and released in accordance with the present invention. I am able therefore, by a combination of the two inventions, to set up connections automatically in either 10 direction over any one or all of three telephone circuits, one of which is a phantom circuit superimposed upon the other two. 15 Having described my invention what I consider to be new and desire to have protected by Letters Patent will be pointed out 20 in the appended claims.

What I claim as my invention is:

1. In a telephone system, an automatic switch, sources of alternating current of different frequency, and means for operating and releasing said switch by current impulses from the said sources, respectively. 25
2. In a telephone system, a line terminating in an automatic switch, sources of alternating current of different frequency, means for controlling the operation of said switch by impulses of current from one of said sources, and means for releasing said switch by an impulse of current from the other of 30 said sources.
3. In a telephone system, an automatic switch, sources of high and low frequency alternating current, means for operating said switch in response to impulses of high 35 frequency current, and means for releasing said switch in response to an impulse of low frequency current.
4. In a telephone system, a line terminating in an automatic switch, sources of alternating current of different frequency, means for connecting said sources momentarily in bridge of said line, a relay associated with said line for controlling the operation of 40 said switch and responsive only to current of one frequency, and a second relay associated with said line and responsive only to current of a different frequency to always release said switch.
5. In a telephone system, a line, a pair of 45 relays associated with said line each responsive only to a particular frequency of alternating current, means for transmitting alternating currents over said line of the proper frequencies to actuate said relays, an automatic switch, an operating magnet in said switch under control of one of said relays, and a release magnet in said switch under control of the other of said relays after a connection is completed.
6. In a telephone system, a trunk line, A. 50 C. generators of different frequency at one end of said line, a pair of tuned relay bridges corresponding to said generators at the other end of said trunk line, an automatic switch having an operating magnet 70 under the control of the relay in one of said bridges, and a release magnet for said switch under control of the relay in the other of said bridges to release said switch at any time during the established connection. 75
7. In a telephone system, a trunk line, A. C. generators of different frequency at one end of said line, a pair of tuned relay bridges corresponding to said generators at the other end of said trunk line, an automatic switch having an operating magnet under the control of the relay in one of said bridges, a release magnet for said switch under control of the relay in the other of 80 said bridges, means including a calling device for transmitting current impulses from one of said generators over said line to operate said switch to establish a connection, and means for transmitting an impulse from the other of said generators over said line 85 to accomplish the release.
8. In a telephone system, a line terminating in an automatic switch, a repeater in said line, means for transmitting impulses of alternating current of a certain frequency over said line to operate said switch through the medium of said repeater, and means for transmitting an impulse of alternating current of different frequency over 90 said line to release said switch through the 95 medium of said repeater.
9. In a telephone system, a line extending through a repeater to an automatic switch, sources of alternating current of different frequency, means in said repeater 100 responsive to current impulses from one of said sources for operating said switch, and means in said repeater responsive to a current impulse from the other source for releasing said switch. 105
10. In a telephone system, a line extending through a repeater to an automatic switch, sources of alternating current of different frequency, a pair of tuned relay bridges in said repeater responsive to current from said sources, respectively, operating mechanism in said switch controlled by the relay in one of said bridges, and release mechanism in said switch controlled by the relay in the other of said bridges. 110
11. In a telephone system, a line extending by way of a repeater to an automatic switch, sources of alternating current of different frequency, a pair of tuned relays in said repeater responsive to current from 115 said sources, respectively, operating mechanism in said switch controlled by one of said relays, and release mechanism in said switch controlled by the other of said relays. 120
12. In a telephone system, a line extend- 130

- ing by way of a repeater to an automatic switch, condensers in the line conductors at said repeater, normally open control circuits incoming to said repeater and switch, respectively, means for transmitting a series of impulses of alternating current over one of said circuits to said repeater, and means in said repeater responsive to the first of said impulses for closing the control circuit to 10 said switch and for producing a momentary interruption therein, and responsive to each subsequent impulse of the series for producing another momentary interruption therein.
13. In a telephone system, a trunk line, a 15 source of alternating current in a normally open bridge of said line at one end, a calling device adapted when operated to produce a series of closures of said bridge to transmit a series of current impulses over said line, 20 and an automatic progressively movable switch at the other end of said line responsive to said impulses to establish a connection, each impulse of current consisting of a plurality of cycles of alternating current.
14. In a telephone system, a trunk line, a 25 source of alternating current in a normally open bridge of said line at one end, a calling device adapted when operated to produce a series of closures of said bridge to transmit a series of current impulses over said line, 30 an automatic switch at the other end of said trunk line and a local control circuit therefor, said switch being operative responsive to interruptions of its control circuit, and a 35 repeater adapted to produce an interruption in said control circuit in response to each impulse received over said trunk line, each impulse of current consisting of a plurality of cycles of alternating current.
15. In a telephone system, a trunk line, a 40 simplex circuit superimposed on said line and including the two sides thereof in parallel, direct current apparatus for operation over said simplex circuit, an automatic 45 switch, and means for operating and releasing said switch by impulses of alternating current transmitted over the metallic circuit
- including the two sides of said trunk line in series.
16. In a telephone system, a trunk line 50 connecting two exchanges having a simplex circuit superimposed on said trunk line, which is provided with quadruplex equipment at each end thereof, operated from sources of direct current for controlling a 55 pair of control circuits, one control circuit comprising the polar side and the other comprising the neutral side of said quadruplex equipment, an automatic trunking switch, a third control circuit comprising the two 60 sides of said trunk line in series for controlling said automatic switch, and means for including a source of alternating current in said third control circuit to control said automatic switch to extend a connection. 65
17. In a telephone system, an automatic switch, a trunk line leading to said switch terminating in a jack, a source of alternating current, a plug ending operator's cord circuit, said plug adapted to be inserted in 70 said jack and having means associated therewith controlled by the operator for operating said switch to extend a connection from said trunk line, and means responsive to the removal of the plug from said jack for automatically connecting said source of current 75 to said trunk line to release said automatic switch.
18. In a telephone system, an automatic switch, a trunk line leading thereto terminating in a jack at the operator's position, a source of alternating current, a quick and a slow relay associated with said jack, a plug for said operator for insertion in said jack, and means associated with the jack for 80 operating the switch to extend a connection from the trunk line, said relays responsive to the removal of the plug from the jack for connecting said source of alternating current to the trunk line momentarily to release 85 said connection.

Signed by me at Chicago, Cook county,
State of Illinois, this 8th day of June, 1917.

ARTHUR BESSEY SMITH.
